UNITED STATES PATENT OFFICE

JACOB KAUFMANN, OF PHILADELPHIA, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

LOOM-HARNESS.

1,090,858.

Specification of Letters Patent. Patented Mar. 24, 1914.

Application filed October 8, 1912. Serial No. 724,539.

To all whom it may concern:

Be it known that I, JACOB KAUFMANN, a citizen of the United States, residing at Philadelphia, in the county of Philadelphia and State of Pennsylvania, have invented certain new and useful Improvements in Loom-Harness, of which the following is a specification.

My invention relates to loom harness, and more particularly it relates to the formation of the individual heddles for controlling the warp ends, whereby said heddles may be readily and easily successively selected for the purpose of inserting the warp ends in their respective heddles.

My invention contemplates a novel formation of heddles which are made of thin flat metal or wire, it heretofore having been found quite difficult to readily and rapidly successively select the individual heddles of this type for the purpose of drawing in or entering the warp ends through the eyes thereof.

The object therefor of my invention is to provide heddles of the aforesaid type with means whereby certain portions thereof will be maintained separated so that the heddles may be selected quite readily.

The nature and characteristic features of my invention will be more readily understood from the following description, taken in connection with the accompanying drawings forming part hereof, in which—

Figure 1 is an elevation of a portion of a harness frame having heddles embodying the main features of my present invention shown mounted therein. Fig. 2 is a transverse horizontal section, enlarged, taken on the line 2—2 of Fig. 1, illustrating how certain portions of the heddles are maintained separated a uniform distance from each other whereby the heddles may be successively selected for the purpose of drawing in or entering the warp ends in the eyes; and Figs. 3 and 4 are enlarged side elevations of the upper portions of the two forms of heddles which are used conjointly in the preferred form of my invention.

Referring to the drawings, in the particular embodiment of my invention therein shown, the harness frame comprises the usual upper and lower bars 5 and 6, which are connected by the end straps 7, in which ends straps the heddle supporting rods 8

and 9 are mounted. The heddle frame 55 proper may be of any preferred construction, such for example as shown and described in detail in Letters Patent No. 980,285 granted to me January 3, 1911, but it should be understood that the particular 60 form of the heddle frame forms no part of my present invention.

Upon the rods 8 and 9 the heddles are mounted in the usual manner, and these heddles in the preferred manner of carrying out my invention comprise two types A and B which are alternately arranged upon the rods 8 and 9 as clearly shown in Fig. 1 of the drawings. The heddle of the type A, near one of its mortised ends, has 70 a portion 10 which is offset slightly out of the main plane of the heddle proper, the offset being of an extent corresponding to the amount which it is desired to separate certain portions of the heddles for the purpose 75 of successively or otherwise selecting the same. The longitudinal extent of the offset portion 10 may be of any desired dimension, depending on the particular manner in which the heddles are operated upon during 80 the drawing in or entering operation. The heddle of the type B is also provided with an offset portion 11, which extends out of the main plane of the heddle proper a distance approximately double that of the offset portion 10 of heddle A, and of a longitudinal extent somewhat greater than that of said offset portion of heddle A, extending both 85 above and below the offset portion 10 of heddle A. As before stated, the heddles of 90 types A and B respectively are arranged alternately in the harness frame as shown in Fig. 1 of the drawings, whereby there is provided a certain portion of each heddle which is spaced a uniform distance from a 95 corresponding portion of the next adjoining heddle, which distance is maintained notwithstanding the flexible character of the heddles made from thin flat metal or wire. It will be seen by an inspection of Fig. 1 100 that on account of the offset portion 11 of heddle B being of a greater longitudinal extent than the offset portion 10 of heddle A, there is provided an appreciable bearing at each end of the offset which will maintain 105 the offset portions at uniform distances from each other the bearing points being indicated at 12, 13, 14 and 15. The lowermost por-

tions of the heddles may also be provided with offset portions 16 and 17 of heddles A and B respectively, and which respectively extend to the left and right for the 5 purpose of maintaining the substantial parallel alignment of the heddles in the frame. It will be seen however, that the offsets 16 and 17 are not for the same purpose as those at the upper end as there is not necessarily 10 provided any portion which is maintained separated from the complementary portion of both adjoining heddles.

The ends of the heddles of both types may be mortised or otherwise formed in any desired manner for mounting on the rods 8 and 9, the particular form which has been arbitrarily selected for the purpose of illustration in the drawings being that which is more particularly shown and described in 15 Letters Patent No. 996,650, granted to me July 4, 1911, but it will of course be understood that any other desired means of mounting the heddles in the harness frame may be employed. The warp eye 18 may 20 also be of any desired form.

It will be seen that by the present invention there are provided flat metal heddles each having certain portions which will be maintained a fixed distance from the corresponding portions of each of the adjoining heddles, notwithstanding the flexible character of heddles of this type, so that it will be possible to employ the well known automatic machines for entering or drawing in 30 the warp ends through the eyes of the heddles, it having heretofore not been possible to employ these machines in connection with the flat metal heddles, and furthermore 35 where the warp ends are drawn in by hand the operation will be greatly facilitated where heddles of the present invention are 40 employed.

Having thus described the nature and characteristic features of my invention what I claim as new and desire to secure by Letters Patent is:—

1. In harness for looms, a plurality of heddles mounted in a suitable frame, said heddles being arranged in pairs, one of each pair having a portion offset out of the main plane of the heddle proper, and the other of each pair having a similarly located portion offset out of the main plane of the heddle proper to an extent substantially double that of the offset portion of the other heddle. 55

2. In harness for looms, a plurality of heddles mounted in a suitable frame, said heddles being arranged in pairs, one of each pair having a portion offset out of the main plane of the heddle proper, and the other of each pair having a similarly located portion offset out of the main plane of the heddle proper to an extent substantially double that of the offset portion of the other heddle and of a longitudinal extent greater than that 60 of the offset portion of the other heddle. 65

3. In harness for looms, a plurality of heddles mounted in a suitable frame, said heddles being arranged in pairs, one of each pair having a portion offset out of the main 70 plane of the heddle proper, and the other of each pair having a portion offset out of the main plane of the heddle proper to an extent substantially double that of the offset portion of the other heddle and extending 75 above and below the offset portion of the other heddle.

In testimony whereof, I have hereunto signed my name in the presence of two witnesses.

JACOB KAUFMANN.
